GEORG SPIESS, OF LEIPZIG, GERMANY

CROSS FOLDING MACHINE

Application filed January 26, 1932, Serial No. 588,861, and in Germany January 31, 1931.

I have filed an application in Germany on the 31st of January, 1931.

In the known cross folding machines of the general type described in my prior U. S. Patent No. 1,725,837, in which the sheet is checked by impact with a stop and is buckled or bent at the folding position by the action of feed rollers, it is necessary when feeding the sheets separately and consecutively, to let the feed device of the corner feed table and at least the rollers of the first cross folding apparatus, run at a higher speed than the folding rollers of the folding apparatus arranged anterior to the corner feed table, in order that a sheet moved upon the corner feed table towards the cross folding apparatus should leave the corner feed table entirely or substantially entirely before the following sheet reaches, with its leading edge, the corner feed table. In the known arrangements it is essential that contact of a sheet reaching the corner feed table with the sheet previously put upon the corner feed table be avoided, so as not to incur the risk of the second sheet being pushed into the open end or folding mouth of the preceding sheet.

A high feed speed or end speed of the corner feed table is, however, detrimental to a satisfactory registration of the sheets. It is most important that the folding speed in the first cross folder should not exceed a certain magnitude as otherwise the accuracy of folding deteriorates excessively even though the folding line of the sheet is pre-shaped before the folding operation proper. If in the known cross folding machines in which the sheet is bent or buckled before the actual folding operation, the folding speed of the first cross folder is kept sufficiently low to ensure a satisfactory folding, the maximum capacity of the first folder can not be fully utilized, as the sheets cannot be fed so as to follow immediately upon each other but must be fed intermittently or with an interval, or the speed of the first folder must be reduced below the normal degree.

One of the objects of the present invention is to avoid these drawbacks. The in-

vention consists substantially in conveying the folded sheets delivered by the first folder in such a manner to the following corner feed table that the sheets whilst moving in the direction towards the following cross folder overlap each other. This partial superimposing of the folded sheets may be effected by any suitable means, for instance by the provision of suitable pushing delivery rollers and guide members provided at the delivery end of the first folder. When applying the invention to multiple folding machines, the superimposing of the folded sheets may, of course, be applied at every corner feed table, that is, anterior to every cross folder.

In a preferred construction according to the invention the folded sheets are conveyed by pushing delivery rollers to a conveyer table arranged at a somewhat lower level so as to provide for a slight drop at the point at which the folded sheets are transferred from the delivery end of one folder to the feed end of the following folder, and suitable guide tongues are provided at this point in such a manner as to insure that the leading edge of a folded sheet issuing from the pushing delivery rollers is moved over the open end of the previous folded sheet which is being conveyed transversely to the corner folder. These guide tongues assist in obtaining the required overlapping and the proper positioning of the folded sheets upon the corner table leading to the following folder.

It is preferred to provide the feeding means, for instance, feed rollers, of the corner feed table with counter rollers preferably in the form of rotary brushes the pressure of which may be controlled and also a guide plate under which the folded sheet, after having been dropped from the guide tongues, passes. The folded sheet performs, whilst dropping upon the preceding sheet, a movement parallel to itself and covers a very considerable portion of the preceding sheet. Owing to the force of inertia imparted to a folded sheet by the pushing delivery rollers, and also owing to the action of the brush rollers, a folded sheet whilst being conveyed

in a transverse direction towards the following cross folder is moved simultaneously against a registering rule, and simultaneously the open end of the folded sheet is closed by the brush rollers, so that the guide tongues are always located at a considerably higher level than the upper edge of the open end of the previously deposited folded sheet. This arrangement effectively prevents a folded sheet which is being deposited upon a corner feed table from accidentally entering the open end of a previously deposited sheet. The invention enables the conveying speed of a corner feed table and the folding speed of the cross folder fed by the table to be maintained equal to or even less than the speed of the preceding folder, and this advantage is attained whilst maintaining an uninterrupted feed of the sheets into the folding machine and employing the most favourable speed within the first folder. Another advantage of the invention resides in an improved registration of the sheets and in slowing down the actual folding operation within the second folder, which results in a much more accurate and satisfactory folding action.

The accompanying drawing shows diagrammatically one construction embodying the features of the invention, all parts unnecessary for the understanding of the invention being omitted.

Fig. 1 shows a simple cross folding machine in elevation said machine being suitable for effecting two parallel folds and one cross fold.

Fig. 2 is a top view corresponding to Fig. 1,

Fig. 3 shows in detail the action and arrangement of the drop stage between the parallel folder and the corner feed table,

Fig. 4 shows in detail the arrangement of the adjustable brush rollers of the corner feed table.

The sheets are conveyed continuously in known manner by means of a feed table 1 mounted in a frame 2 and provided with a lateral registering rule 100 to a pair of rollers 4, 7 driven in known manner from a shaft 3, and are fed by the rollers 4, 7 into an upper folding table or pocket 8. In this pocket the leading edge of the sheets is checked by a stop 80 so that the sheet contained in the table or pocket owing to its being pushed from behind by the roller pair 4, 7, is buckled or bent at the forward end of the folding pocket 8. The buckled or bent portion is gripped by the roller pair 4, 5 and the sheet is then folded and moved by the rollers 4, 5 into a lower folding pocket 9, in which the leading edge of the sheet is checked by a stop 90. Owing to the rollers 4, 5 continuing to push the sheet, the sheet is again buckled or bent at the forward end of the second folding pocket

9 and enters the rollers 5, 6, which grip the sheet and fold same a second time parallel to the first fold. After being folded by the rollers 5, 6, the sheets are conveyed to a corner feed table 16 by delivery rollers 10, 11 over a delivery table 12 and by a further delivery roller 14 which co-operates with guide rollers 15. Upon the delivery table 12 are provided guide tongues 13 which pass through the roller pair 14 and 15 and extend approximately to the height of the lateral edge of the corner feed table. The corner feed table is located at a lower level than the table delivery roller 14, see particularly Fig. 3, so that each sheet issuing from the roller pair 14, 15, comes into contact with the corner feed table only when the leading or forward edge of the sheet reaches about the longitudinal middle line of the corner feed table. Consequently, each sheet which has been completely deposited upon the corner feed table and is being conveyed upon the corner feed table to the following cross folder, will be partly covered by the subsequent sheet, see also Fig. 2, a perfectly reliable sliding of the superimposed sheet over the preceding sheet at the time of the deposition being insured by the guide tongues 13 which lie above the corresponding edge of the corner feed table 16. Proper covering and overlapping will therefore take place even in cases in which a deposited folded sheet should have the tendency to open at its rear end. As there is no risk of a subsequent sheet being inserted into the open end of a sheet previously deposited upon the corner feed table, the rollers 16a of the corner feed table and consequently the rollers of the cross folder fed by the table may be allowed to run at a lower speed. This reduction of the speed of the feed table and the cross folder may be so high that the actual working speed of the cross folder need not be higher than the speed of the previous folder. A perfect folding may, therefore, be obtained whilst maintaining a continuous supply of sheets. In other words, it is not necessary to provide for an interval between two following sheets in the first feed of the folding machine in order to compensate for the difference in the speeds of the two following folders.

The corner feed table is provided in known manner with an adjustably mounted registering rule 17. Upon this rule is mounted an adjustable riding support 18 which may be clamped in any desired position upon the rule and carries by means of a pivot pin 19 parallel to the conveying rollers 16 a double armed lever 20. The longer arm of the lever 20 carries upon its end a brush roller 21, whilst the shorter arm of the lever rests upon a set screw 23 provided with a counter nut 22, whereby the pressure of the brush roller upon the sheet

being conveyed by the feed rollers 16a of the corner feed table may be regulated at will. The riding support 18 carries also a guide plate 24, which guides the sheet into 5 position under the brush roller. If required two or more brush rollers may be provided.

Owing to the yielding and soft pressure exerted by the brush rollers, the deposited sheets are immediately and reliably pushed 10 by the feed rollers against the registering rule and they cannot, even at very high working speed, slide back. The partial overlapping of the sheets upon the corner feed table enables the folded sheets to be conveyed 15 to the following cross folder 25 very closely one after the other, so that the required folding operations can be satisfactorily performed notwithstanding the fact that the sheets are continuously and without 20 any interval fed by the first feed table. 1. The peripheral speed of the folding rollers of the cross folder need not, as in the hitherto known constructions, be greater by about one half than the peripheral speed 25 of the folding rollers 4, 5, 6 of the preceding folder, but it may be approximately the same or even lower than the speed of the rollers 4, 5, 6. The folding rollers of the cross folder 25 are driven from the preceding 30 roller through a bevel gear 26. The slow folding speed within the cross folder and the slow feed of the sheets towards the cross folder leads to a very accurate registration of the sheets along the registering rule of the corner feed table and it also results 35 in a very accurate folding, and owing to the reduction of the discharge speed, a very gradual and reliable discharge upon the delivery stack 27 is insured.

40 I claim:

1. In cross folding machines the combination of: a first folder; a second folder; means for transferring sheets folded within the first folder to the second folder, said 45 means comprising a corner feed table; and means for partly superposing the folded sheets coming from the first folder whilst delivering same to the corner feed table, whereby the folded sheets are delivered to 50 the second folder in such a manner that each sheet is overlapped by the following sheet, substantially as described.

2. In a cross folding machine of the type referred to, the combination of: a first folder; a second folder; means for transferring the folded sheets from the first folder to the second folder, said means comprising a corner feed table; and means for superposing the folded sheets during delivery on to 55 the corner feed table, said superposing means comprising a pair of pushing delivery rollers and guide tongues co-operating therewith, substantially as described.

3. In a cross folding machine of the type referred to, the combination of: a first fold-

er; a second folder; a corner feed table interposed between the said two folders; means for delivering the folded sheets from the first folder to the said corner feed table, said means comprising pushing delivery 70 rollers and guide tongues, said guide tongues being situated at a higher level than the corner feed table and projecting over the corner feed table, substantially as described.

4. In a cross folding machine of the type referred to, the combination of: a folder; a second folder; means for transferring the folded sheets from the first folder to the second folder, said means comprising a corner feed table; means for partly superposing the folded sheets during their delivery upon the corner feed table; and means for pressing the delivered sheets upon the corner feed table, said means comprising brush 75 rollers, substantially as described. 80

5. In a cross folding machine of the type referred to, the combination of: a folder; a second folder; means for delivering the folded sheets from the first folder to the second folder, said means comprising a corner feed table provided with feed rollers arranged at an angle other than 90° to the direction of the feed; means for partly superposing the folded sheets during their delivery upon the corner feed table; and means for pressing the deposited sheets against inclined feed rollers, said means comprising brush rollers, adapted to rotate about axes parallel to the inclined feed rollers, substantially as described. 90 95

6. In a cross folding machine of the type referred to, the combination of: a folder; a second folder; means for transferring the folded sheets from the first folder to the second folder, said means comprising a corner feed table; means for partly superposing the folded sheets during their delivery upon the said corner feed table; the folding speed of the second folder not being greater than the folding speed of the first folder, substantially as described. 100 105 110

Signed at Leipzig, Germany, this eighth day of January, 1932.
